J. C. STILES

TELEPHONE SYSTEM

Filed April 28, 1921

UNITED STATES PATENT OFFICE.

JOHN C. STILES, OF ST. LOUIS, MISSOURI.

TELEPHONE SYSTEM.

Application filed April 28, 1921. Serial No. 465,206.

To all whom it may concern:

Be it known that I, JOHN C. STILES, a citizen of the United States, residing at the city of St. Louis, in the State of Missouri, have 5 invented certain new and useful Improvements in Telephone Systems, of which the following is a specification.

My invention has relation to improvements in telephone circuits and consists in 10 the novel features of construction more fully set forth in the specification and pointed out in the claim.

The object of the present invention is to provide a system of telephone circuits that 15 may be applied to party lines, whereby one party on the line may speak to an outside party without being in circuit with another party on his line, so that parties cannot listen in on each other. A further object is 20 to provide a telephone system wherein parties on the same line may speak to each other to the exclusion of other parties on the line.

Further and other advantages will be better apparent from a detailed description of 25 the invention in connection with the accompanying drawing, which is a diagrammatic view of my improved telephone circuit showing the connections and arrangements of 30 switches whereby I accomplish the desired result.

Referring to the drawing, 1 represents a battery supplying energy to the line wires 2 and 3, and 4 represents a reversing switch connected across said wires. A polarized 35 relay 5 operates to cut out of circuit the phones 6, 7, 8, 9, except the one that is being used.

The phones 6, 7, 8 and 9 are in series with 40 coils 10, 11, 12, 13, respectively, said coils however, being connected in multiple and 45 all of them being in series with the armature 14 of the relay 5. Armature 14 is connected to line 3 by the conductor 15.

The invention can best be understood by 45 tracing the respective circuits. When none of the phones are in use, of course, all the phone circuits are open; but as soon as the receiver of any phone is picked up the circuit of that phone is immediately closed as 50 well understood in the art.

Connected in series with line wire 2 is the coil 16 of the relay 5, said coil also being in series with conductor 17. Conductor 17 it

will be observed is in series with all of the telephone circuits, the phone circuits being 55 connected in multiple as follows:

Coils 10, 11, 12 and 13 are connected to conductor 17 by conductors 18, 19, 20 and 21 and to the phones 6, 7, 8, 9, by conductors 22, 23, 24, 25, which terminate at contacts 60 26, 27, 28, 29, (in the phone) respectively. Conductors 30, 31, 32, 33 have connection with the hook 34, 35, 36, 37 whence they go to the armature 14 of the relay 5, and contact with said armature when it is in either 65 neutral position or attracted by pole B of the relay. The conductors 30, 31, 32, 33 are connected to line wire 3 by conductors 38, 39, 40, 41, switches 42, 43, 44, 45, and conductors 46, 47, 48, 49. 70

The operation of my invention will now be described. Assume a party desires to use 75 phone 6. When the receiver is taken off the hook the phone circuit is closed as follows:

Line wire 2, coil 16, conductor 17, conductor 18, coil 10, conductor 22, contact 26, hook 34, conductor 30, armature 14, conductor 15, line wire 3. The closing of this circuit energizes coils 16 and 10, causing pole A to attract armature 16 opening the 80 phone circuits at this point, and closing the circuit of phone 6 through the attraction of armature 42 to conductor 38 whence the circuit is completed thru 46 and 15. However, none of the other phones will be on 85 closed circuit because their armatures (43, 44 and 45) could not be attracted since their respective receivers are on the hooks and the circuit open. Should any one of the other parties lift his receiver off while phone 90 6 is engaged he will not be able to listen in because his circuit is open at armature 14 (the same still being attracted to the left). As soon as phone 6 has its receiver replaced on the hook 34 the circuit will again be open and armature 14 restored to neutral position 95 in contact with conductors 30, 31, 32, 33. The above described operation takes place irrespective of which phone is used. It is thus seen that I have provided an electrically controlled switch (armature 14) for opening all the phone circuits when one is 100 in use, and simultaneously closing at another point the circuit of the phone that is being used.

Suppose one party wishes to speak to an-

other party on the same line, for example, phone 6 with phone 9. In this instance the operator reverses the circuit in the coil 16 by means of the reversing switch 4 causing 5 the armature 14 to be attracted to pole B where it remains in contact with conductors 30, 31, 32, 33. Phone 9 is then signalled and on taking up the receiver its circuit is closed in the same manner that that of 10 phone 6 was closed (through the attraction of armature 45 to conductor 41). Phones 6 and 9 are now both in circuit with line wires 2, 3, and the operator again reverses 15 the switch 4 causing armature 14 to be attracted to pole A and opening the circuits of phones 7 and 8 at this point so that they cannot get into circuit with 6 and 9.

From the foregoing it is apparent that 20 the relay 5 may be controlled to permit parties on the same line to be connected without other parties on the line listening in.

Having described my invention, I claim:

A telephone system including, in combination, a source of electrical current, a pair 25 of line wires leading therefrom, a reversing switch connected across said wires, a polarized relay including a coil connected in series with one of the said line wires and including also an armature, a connecting conductor between the said armature and the other one of the said line wires, a plurality 30 of phone circuits including coils and phones connected in series with the said coils, the said coils of the phone circuits being connected in multiple and all of them being in series with the said armature of the polarized relay, and a conductor in series with the said coil of the relay and in series also 35 with all of the said phone circuits.

40 In testimony whereof I hereunto affix my signature.

JOHN C. STILES.
